CLAIM

The ornamental design for control unit for room automation, as shown and described.

DESCRIPTION

FIGURE 3.1 illustrates an elevated, angled view of a control unit for room automation.

FIGURE 3.2 illustrates a front view of a control unit for room automation.

FIGURE 3.3 illustrates a back view of a control unit for room automation.

FIGURE 3.4 illustrates a top view of a control unit for room automation.

FIGURE 3.5 illustrates a bottom view of a control unit for room automation.

FIGURE 3.6 illustrates a side view of a control unit for room automation.

FIGURE 3.7 illustrates another side view of a control unit for room automation.

Broken lines are not part of the claimed design.
